UNITED STATES PATENT OFFICE.

JOHN F. SCHENCK, JR., OF SHELBY, NORTH CAROLINA.

SLIVER-LAP MACHINE.

Application filed September 15, 1922. Serial No. 583,367.

To all whom it may concern:

Be it known that JOHN F. SCHENCK, Jr., a citizen of the United States, residing at Shelby, in the county of Cleveland and State of North Carolina, has invented new and useful Improvements in Sliver-Lap Machines, of which the following is a specification.

This invention relates to cotton spinning machinery and particularly to an improvement in sliver lap machines and the like, and proposes the construction of novel means for releasing the lap from the driving rolls at the time of doffing the full lap.

As is well known to those skilled in the art, a number of card slivers are taken by the sliver lap machine subjected to draft to draw the fibers into parallelism and formed into a wide lap or ribbon which is wound into a roll by the sliver lap machine from which it is taken or "doffed" to be subjected to later processes in its course through the mill. In present lap machines the lap is wound upon a roll by frictional contact of that part of the lap already wound with the driving rolls. The operation of doffing requires that the fully wound lap roll be raised out of engagement with the drive rolls so that the filled roll may be removed and an empty roll substituted therefor. This, in ordinary practice, is accomplished by manipulation of a hand wheel at the side of the machine and requires that the operative, whose normal work demands that he stand in front of the machine, facing the roll, shall be forced to reach over to one side, bending his body almost at right angles. As the sliver lap machine must be doffed every eight or ten minutes and each operative attends from three to six machines, it is obvious that the labor is fatiguing and the capacity of the operative necessarily limited.

One of the objects of the present invention is to substitute, for the usual hand wheel, means for releasing the wound lap from the drive rolls accessible to the operative from his standing position and automatically returnable to normal position after having been actuated.

Another object of the invention is the provision of lifting means for the lap roll within easy reach of the operative from his standing position, normally inactive during the self-rise of the lap while building up on the roll, and manually operable to engage with lap roll raising mechanism to lift the

lap from the drive rolls, there being automatic means associated with said lifting means to cause its release from said lap roll raising mechanism and its return to normal position.

Specifically, the object of the invention is the construction of a hand lever journaled upon the lap roll lifting shaft of a sliver lap machine and engageable with said shaft at will by manipulation of a pawl and ratchet mechanism to operate said shaft, and means associated with said lever for causing its automatic return to normal position.

With the above and other objects in view, my invention consists in the improved sliver lap machine illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:

Figure 1 is a side view of a portion of a sliver lap machine having an embodiment of my invention applied thereto.

Figure 2 is a side elevation of the machine illustrated in Figure 1 the hand lever being shown in full lines in engaged position with the ratchet on the lap roll lifting shaft, and in dotted lines in disengaged position.

Figure 3 is an end view of the sliver lap machine.

Figure 4 is a view in perspective showing my improved hand lever.

Referring now in detail to the several figures, the numeral 1 represents the frame of the sliver lap machine which supports bearing blocks 2 and 3, each of which affords bearings for the friction drive rolls 4 and 5. These drive rolls are driven by a single intermediate gear 6 from a source of power, not shown, and they therefore rotate in the same direction. A sliding frame formed by a pair of uprights 7 and 8, best shown in Figure 3, is positioned in a plane passing between said rolls at their point of closest approach, said frame carrying bearing blocks 9 and 10, Figure 3 in which is journaled a shaft 11. The bearing block 9 and the outer end of the shaft 11 are formed with complementary breech block elements 12 and 13 and the shaft 11 is provided with a hand wheel 14, so that when the hand wheel is

partially turned the breech block elements 5 disengage and the shaft 11 can be drawn longitudinally from the frame. A removable wooden roll 15 is journalled upon the shaft 11 which may be removed by withdrawing said shaft and replaced by another roll in the course of operation of the machine, as will presently be described. A pair of disks 16 and 17 are secured to the bearing blocks 10 9 and 10 respectively and approach closely to the ends of the roll 15 so as to form plane ends to the lap as it is wound upon the rolls.

When the winding of the lap commences the roll 15 lies in contact with the feed rolls 15 4 and 5 and is rotated thereby. As the diameter of the rolled lap increases the roll 15 rises, the driving draft being imparted to it through the layers of lap already wound. When the roll 15 has been filled it must be 20 taken away from the machine or doffed and an empty roll substituted in its place for the continuation of the winding operation. In order to raise the full lap from the driving rolls, the uprights 7 and 8 are provided 25 along their lower portions with racks 18 and 19 which engage pinions 20 and 22 keyed to the lap roll lifting shaft 21. Normally, when the frame rises due to the increasing thickness of the rolled lap, the lifting shaft 30 21 idly rotates through the action of the racks 18 and 19 upon the pinions 20 and 22. The shaft 21 is provided with a foot brake in the form of a drum 23 keyed to said shaft and engaged by a brake shoe 24 secured in 35 intermediate the ends of the pivoted foot lever 25. This lever is weighted by the shiftable weight 26 to normally maintain the brake shoe 24 frictionally against the drum 23 for the purpose of winding the lap under pressure, making it firm and of smaller diameter 40 for the number of yards of cotton than it would be if wound with no pressure on the drum.

On the outer end of the lap roll lifting shaft 21 is secured a pinion 27 adjacent to which the hand lever 28 is journalled. This lever is preferably formed with a yoke 29 carrying a bearing 30 so that the hand lever is journalled on opposite sides of said pinion, 50 and a small pawl 31 is pivotally mounted on said yoke and arranged to engage the teeth of the pinion 27. The pawl 31 is connected to an operating link 32 actuated by a hand bell-crank 33 and normally tensioned by a 55 spring 34 in a direction to hold the pawl 31 out of engagement with the teeth of the pinion 27. The lower end of the hand lever 28 is provided with a weight 35 so that said lever maintains a position by gravity with 60 its upper end within easy reach of an operative standing in front of the machine and facing the lap roll 5.

In the operation of the sliver lap machine the lap is wound upon the roll 15 by frictional engagement of the drive rolls 4 and

5 with the outer layer of lap already wound upon said roll. As the roll increases in thickness the uprights 7 and 8 rise turning the shaft 21 idly through the bearings of the hand lever, the latter maintaining its normal position as shown in dotted lines in Figure 2 by virtue of the weight 35. When the lap roll is filled and it is desired to remove it from the sliver lap machine the operative presses the foot lever 25 to release the brake, grasps the hand lever 32 and pushes it downward through an arc of about 15°, as shown in Figure 2. The initial pressure of his grasp actuates the bell crank 33 to throw the pawl 31 into engagement with the pinion against the tension of the spring 34. The downward movement of the lever 32 from its dotted to full line positions is sufficient to enable the pawl 31 to turn the pinion 27 and the shaft 21, to which the pinion is attached, through an angle so as to raise the uprights 7 and 8, lifting the lap roll clear of the drive rolls 4 and 5. The operative then again applies the brake to hold the frame in raised position while he removes the lap roll from the machine. This is done by turning the hand wheel 14 so as to disengage the breech block elements after which the shaft 11 is withdrawn through its bearings sufficiently to permit the roll 15 to be taken out. A new roll is then substituted and the foot brake released. This permits the drum 23 and shaft 21 to revolve freely, and since the pawl 31 acts upon the pinion 27 only in one direction the uprights 7 and 8 descend by gravity until the empty roll makes contact with the drive rolls.

It is apparent that in the manipulation of the several control features herein described the operative is not compelled to materially alter his standing posture in front of the machine facing the lap roll, the controls being all within easy reach and no bending of the body is called for. The labor of doffing the machine is therefore made much easier and one operative is enabled to attend a larger number of machines.

Although I have described my invention in its preferred embodiment in combination with a sliver lap machine it is well within the spirit of the invention to combine it with the mechanism of ribbon lap, derby doubler or any similar device in which means are provided for disengaging a full roll from a friction drive mechanism for replacement with an empty roll.

Having described my invention what I claim as new and desire to secure by Letters Patent, is:—

1. In a sliver lap machine, a roll-carrying frame, a shaft for elevating said frame, operating means journalled on said shaft and provided with engaging means for engagement with said shaft to rotate the latter for elevating said frame, said engaging

means being releasable from said shaft to permit the descent by gravity of said frame independently of said operating means.

2. In a sliver lap machine, a roll-carrying frame, a shaft for elevating said frame, operating means journalled on said shaft and having a normal position when inoperative, engaging means carried by said operating means for engagement with said shaft to rotate the latter for elevating said frame, said engaging means being releasable from said shaft to permit the descent by gravity of said frame independently of said operating means and means for automatically returning said operating means to normal position.

3. A sliver lap machine, a roll-carrying frame, a shaft for elevating said frame, operating means journalled on said shaft and having a normal position when inoperative, engaging means carried by said operating means for engagement with said shaft to rotate the latter for elevating said frame and being automatically releasable from said shaft to permit the descent by gravity of said frame independently of said operating means, and means for automatically

returning said operating means to normal position.

4. In a sliver lap machine, a roll-carrying frame, a shaft, cooperating means on said shaft and frame for elevating the latter, a pinion on said shaft, an operating lever journalled upon said shaft and having a normal position when inoperative, a pivoted pawl carried by said lever and normally out of contact with said pinion, means for depressing said pawl into engagement with said pinion to permit rotation of said shaft by said lever and a weight secured to said lever to cause the automatic return of the latter to normal inoperative position.

5. In a sliver lap machine having a supporting frame, a roller-carrying frame, a shaft for elevating said roller-carrying frame, a hand-lever journalled on said shaft and provided with means engageable with the teeth of said pinion, means on said hand-lever for actuating the engageable means, the hand-lever projecting upwardly and forwardly to a position above and forwardly of the front of the frame of the machine.

In testimony whereof I affix my signature.
JOHN F. SCHENCK, JR.
